UNITED STATES PATENT OFFICE.

ROBERT H. PLASS, OF UPPER MONTCLAIR, NEW JERSEY, ASSIGNOR, BY MESNE ASSIGNMENTS, TO BEMIS BRO. BAG COMPANY, OF ST. LOUIS, MISSOURI, A CORPORATION OF MISSOURI.

BAG-MAKING MACHINE.

Application filed August 4, 1920. Serial No. 401,103.

To all whom it may concern:

Be it known that I, ROBERT H. PLASS, a citizen of the United States of America, residing at Upper Montclair, county of Essex, State of New Jersey, have invented certain new and useful Improvements in Bag-Making Machines, of which the following is a specification.

My invention comprises automatically operating apparatus for cutting, folding, printing and sewing fabric to form bags thereof, and involves certain improvements on the invention shown and described in my Patent No. 1,054,867, granted March 4th, 1913. 10
15 The best form of apparatus at present known to me embodying my invention is illustrated in the accompanying twenty-eight sheets of drawings, in which:

Fig. 1 is a side elevation of the cloth-printing and folding apparatus and the associated cloth feeding mechanism, and a section through certain mechanism connected thereto taken on the line 1—1 of Fig. 28.

Fig. 2 is an end elevation of the portion of 20 the machine shown in Fig. 1, and a side elevation of a portion of the intermittent-feed apparatus for handling the printed and folded cloth.

Fig. 3 is a vertical section, on an enlarged scale, of the cloth-cutting mechanism and of the intermittent-feed mechanism therefor partially shown in Fig. 2, the section being taken on line 3—3 of Fig. 5, and other parts being broken away.

Fig. 4 is a vertical section on line 4—4 of Figs. 28 and 10 showing the cloth-cutting and transfer table mechanisms and parts of the sewing mechanism, other parts being broken away.

Fig. 5 is a general plan view of that portion of the mechanism shown in Fig. 3, the vertically reciprocating blade of the shears being removed and its housing shown in section on the line 5—5 of Fig. 3, and other parts being broken away.

Fig. 6 is a vertical section of the transfer table mechanism, taken on line 6—6 of Fig. 8, other parts being broken away.

Fig. 7 is a vertical section, on line 7—7 of Fig. 9, through the sewing, thread-cutting and delivery end of the machine, Figs. 6 and 7 together forming a complete section of the whole machine on the line 6—7 of Fig. 28.

Fig. 7^a is a detail view of the fly-sticks of

the delivery mechanism showing them in a different position from that shown in Figs. 7 and 26.

Fig. 8 is a plan view of the transfer table mechanism shown in Fig. 6, and also 60 of the cloth-cutting mechanism.

Fig. 9 is a plan view of the sewing and thread-cutting mechanism and delivery end of the machine shown in Fig. 7, and adjoining the plan view shown in Fig. 8. 65

Fig. 10 is a horizontal section on line 10—10 of Fig. 4.

Fig. 11 is a horizontal section on line 11—11 of Fig. 7, of the parts adjoining those shown in Fig. 10. 70

Fig. 12 is a detail vertical section of the printing mechanism, on an enlarged scale, taken on line 12—12 of Fig. 13, showing the feed roll, platen roll and plate rolls, in cross section. 75

Fig. 12^a is a general, diagrammatic, cross-sectional view of the platen and printing rolls, with the inking rollers indicated in dotted lines.

Fig. 13 is a detail vertical section on line 13—13 of Fig. 12, taken longitudinally of the rolls, parts being broken out. 80

Fig. 13^a is a diagram of the electrical connections of the reversing electric motor for the cloth-folding or cloth-doubling and centering apparatus shown in detail in Figs. 15, 16 and 17. 85

Fig. 14 is an elevation of the printing mechanism shown in Fig. 13, parts being broken out and others shown in cross section. 90

Fig. 15 is an enlarged, detail vertical section of the cloth-folding or cloth-doubling and centering apparatus, taken on broken line 15—15 of Fig. 16. 95

Fig. 15^a is a diagrammatic view, showing the method of folding or doubling the cloth, taken on line 15^a—15^a of Fig. 16, parts being broken away.

Fig. 15^b is a detail plan view of the current reversing contact mechanism for operating the reversing electric motor (shown in diagram in Fig. 13^a) for adjusting the V-shaped frame of the cloth-centering mechanism. 100

Fig. 16 is a vertical central section of this V-shaped frame and associated frame-adjusting and cloth-guiding mechanism, the section being taken on line 16—16 of Fig. 15. 105

Fig. 17 is a diagrammatic view of the in- 110

clined V-shaped frame, looking down on it in a direction at right angles to its plane, parts of its associated supporting and operating connections being broken away, and 5 the adjustable and adjusting parts being shown in a changed position in dotted lines.

Fig. 17^a is a detail front view of one of the movable fingers for controlling this adjustment, parts being broken away.

10 Fig. 17^b is a similar side view of the same, its supporting bar being shown in section.

Fig. 17^c is a detail cross section, on line 17^c—17^c of Fig. 17, parts being supplied which are not shown at that end of Fig. 17.

15 Fig. 17^d is a detail vertical cross section on broken line 17^d—17^d of Fig. 17, parts being supplied not shown in Fig. 17.

Fig. 18 is a vertical cross section on line 18—18 of Fig. 3, showing the mechanism 20 for shifting the intermittent-feed apparatus.

Fig. 19 is a similar view on line 19—19 of Fig. 3.

Fig. 20 is a vertical cross section on broken line 20—20 of Fig. 3, showing the shears of 25 the cloth-cutting apparatus and operating mechanism therefor.

Fig. 21 is a similar vertical cross section taken on line 21—21 of Fig. 4, also showing the cloth-cutting apparatus and, in addition, the change gear for driving the main 30 shaft A.

Fig. 21^a is a detail side elevation of said change gear and a cross section of the driving shaft, taken on line 21^a—21^a of Fig. 21.

35 Fig. 22 is a vertical cross section of the sewing portion of the machine taken on line 22—22 of Fig. 7 to show the fork which is slid under the bag section, and its operating mechanism, the sewing machines proper being removed and their shafts shown broken away.

Fig. 22^a is a detail view of the actuating bar for the thread-cutting mechanism.

40 Fig. 23 is a detail vertical cross section on line 23—23 of Fig. 7, showing the sewing machine drive and the thread-cutting mechanism, parts being broken away.

45 Fig. 23^a is a detail plan view of the tripping and resetting apparatus for the actuating bar (shown in detail in Fig. 22^a) of the thread-cutting mechanism, parts being broken away.

50 Fig. 23^b is a detail side elevation of said tripping and resetting apparatus, parts being shown in section and others broken away, the tripping dog being shown in operative position.

55 Fig. 23^c is a similar detail view of said dog, showing it in tripped position.

60 Fig. 23^d is a detail plan view of one of the thread cutters and its driving gear and ratchet clutch, parts being broken away.

65 Fig. 23^e is a side elevation of the same, the supporting base being shown in section on line 23^e—23^e of Fig. 23^a.

Fig. 24 is a vertical cross section on line 24—24 of Fig. 7.

Fig. 24^a is a detail view of the driving shaft for the pin-sprocket chains for feeding the bag sections through the sewing machines, parts being shown in section and others broken away, and Fig. 24^b is a cross section on line 24^b—24^b of Fig. 24^a.

Fig. 24^c is a detail side view of the clutch-operating apparatus for driving intermittently the delivery belt on which the completed bags are deposited, the driving shaft being shown in cross section taken on line 24^c—24^c of Fig. 24.

Fig. 25 is a diagrammatic side elevation of 80 the intermittent-feed mechanism, the parts being shown at the other extreme of their motion from that shown in Fig. 3.

Fig. 25^a is an enlarged detail of the spring fingers or grippers for feeding the bag-sections from the shears to the transfer table, with a change position of the parts shown in dotted lines, parts being broken away and others in section.

Fig. 25^b is a plan view of the parts shown 90 in Fig. 25^a, and Figs. 25^c and 25^d are cross sections on lines 25^c—25^c and 25^d—25^d, respectively, of Fig. 25^a.

Fig. 26 is a diagrammatic sectional view, on a vertical plane, of the transfer and delivery apparatus, shown in Figs. 6 and 7, but on a smaller scale and with the parts at the other extreme of their motion.

Fig. 26^a is an enlarged detail side elevation and partial section of the pin-sprocket 100 chain mechanism for feeding the bag-sections, parts being broken away, and others shown in section.

Fig. 26^b is a detail side elevation and partial section of the pin-sprocket chain, and 105 Fig. 26^c is a plan view and partial section of the same.

Fig. 27 is a diagrammatic plan view of the vertically reciprocating transfer table and part of the sewing table, parts being 110 shown in section and others broken away, and Fig. 27^a is a similar view of the remainder of the sewing table and the delivery fly-sticks cooperating therewith.

Fig. 28 is a general diagrammatic plan 115 of the entire machine.

Fig. 29 is a plan of a sewed bag-section, a part being broken away and part shown in section.

Fig. 30 is a view of the finished bag produced by turning the sewed bag section of Fig. 29 inside out, and 120

Fig. 31 is a view similar to Fig. 29, of a smaller bag-section in which the fold of the fabric is along one side instead of at one 125 end, and which is sewed along the other side and across one end instead of being sewed along both sides as in Fig. 29.

Throughout the drawings like reference characters indicate like parts. 130

Main driving gear.

Power for operating the machine is derived from electric motor B, (Fig. 7) transmitted through suitable reducing gearing, 6 as C, (Fig. 7) to horizontal driving shaft D which has a squared end D' (see Figs. 8, 10 and 21), which may be grasped by a wrench to partly turn the shaft when necessary, as in changing the gears. From driving shaft D motion is transmitted to main shaft A, at right angles thereto, through helical gearing E and change gears F (Figs. 10, 21 and 21^a). Power for the sewing machines and thread-cutting knives is taken 10 from driving shaft D through spring pressed friction clutch 240^a driving helical gear 240 (Figs. 7, 11), and through vertical jack-shaft 203, and helical gearing 203^a (Figs. 7 and 11) to operate the feeding mechanism for the sewing machines, both of which run continuously. Power for operating all other parts of the machine is derived from main shaft A, being transmitted to the cloth-printing and folding mechanisms at the other end of the machine 15 through double gears 11, 11^a, (Figs. 1, 3, 5 and 18), and to the cloth-cutting and feeding mechanism of the intermediate section of the machine through cams 120 and 149. (Figs. 2, 3, 4, 10, 20 and 25). The vertically reciprocating transfer table 184 (Figs. 4, 6, 8 and 26) and the reciprocating fork 192 of the transfer mechanism are also driven from a cam 191 on shaft A, (Figs. 4, 10 and 26) and the delivery and counting mechanisms at the rear end of the machine are driven by cam 272 also on main shaft A (see Figs. 10 and 26). The main shaft A makes one complete revolution for each complete cycle of the machine, i. e., one revolution for each bag made and printed, whatever the size of the bag. The limit of speed for the machine is the maximum speed of the sewing machines. If the bags being made are large, then the number of bags made per minute is smaller and the speed of revolution of the main shaft A is slower and the cycles of operation of the periodically acting elements of the mechanism, such as the cutting apparatus and printing rolls, are fewer per minute, but the speed of the continuously acting elements, such as the cloth feeders, is approximately uniform 20 for all sizes of bags, as these mechanisms are always driven so as to deliver the cloth to the sewing machines as fast as the latter can handle it.

Printing mechanism.

The printing press operates on the cloth as it comes from the original roll 1 (Figs. 1, 2 and 28). From the roll 1 the cloth 2 runs under guide roller 3, over guide rollers 4 and 5, around and under driving roll

6, (Figs. 1 and 12) around and under platen roll 7, up over guide rods or rollers 8 and 9, and then down to the folding mechanism. As shown in Fig. 1 rollers 8 and 9 are supposed to be supported from the ceiling of the room in which the machine is placed. Motion from main shaft A is transmitted to driving roll 6 through gear 10, double gears 11, 11^a, on counter-shaft 12, gear 13 on shaft 14, (Figs. 1, 2, 3, 5, and 18,) thence through bevel gearing 15 (Fig. 2) to vertical shaft 16, through bevel gearing 17 (Figs. 1 and 28) to horizontal shaft 18 and bevel gearing 19 to cross shaft 20. From the other end of this cross shaft 20 the driving motion is transmitted by change-gear 21 and idler gear 22 to gear 23 (Figs. 12, 14 and 28) on the shaft of driving roll 6. Another gear 24, (Figs. 13 and 14) on the shaft of driving roll 6 near its other end and meshing with idler gear 25, carried on stub shaft 29 mounted in a depending arm from housing 30, transmits motion to gear 26 fast on counter shaft 27 journaled in housing 30. Bevel gear 28, 30 also fast on this counter shaft, transmits motion to bevel pinion 31 on shaft 32, (Figs. 1 and 14) which shaft transmits the driving motion back to the folding rolls 56 and to feeding rolls 57, through bevel gearing 33 (Figs. 1, 2, 15 and 16) and vertical shaft 34.

Motion from vertical shaft 34 is transmitted through bevel gearing 103 (Fig. 2) to horizontal shaft 104 on the end of which is helical gear 105, which transmits such motion to the upper member of the pair of helical gears 106 on the ends of the shafts of feed rolls 57. Similar gearing 105^a and 106^a transmits motion from shaft 104 to folding rolls 56 (Figs. 2 and 16). This train of gearing from driving roll 6 through gears 24, 25, 26, 28 and 31, and shafts 32 and 34, to feed rolls 57 and folding rolls 56, is so proportioned that the circumferential speeds of rolls 6, 56 and 57, are all the same.

Another gear 35 (Figs. 12, 13 and 14) near the first mentioned end of the shaft of feed roll 6 meshes with an idler 35^a, which in turn meshes with gear 36 on shaft 37, from which shaft motion is transmitted to any suitable set of inking rollers indicated at 38 (Fig. 12^a) which cooperate with the printing plate rolls 39, 39, 39, which carry the type or other design to be printed on the cloth as it runs around the platen roll 7. This gearing and the inking mechanism are not illustrated in detail as they are of standard construction.

Gear 35 also meshes with larger gear 43 on the shaft of the platen roll 7, and drives the same at the same circumferential speed as driving roll 6. The printing plate rolls 39 are journaled in sliding journal boxes 40,

40, which are movable in guides 41, 41, in sub-frame 49, (Fig. 12) along lines radial to the platen roll 7, and which boxes may be forced toward the platen roll by screws 5 42, 42.

These printing rolls are driven (independently of the gearing which drives the platen roll) from gear 44 on the end of cross shaft 20, opposite that which carries gear 21, employed for rotating the driving roll 6 and platen roll 7, through the above described train of gearing 22, 23, 35, 43. This gear 44 (Figs. 1, 14 and 28) meshes with idler train 45, the last gear of which 15 meshes with the gear 46 on the shaft of one of the printing rolls 39. Each other printing roll 39 has a similar gear 46 and they are rotated in unison by idler 47, which is loosely mounted on the shaft of platen roll 20 7 (Figs. 1 and 13). The stub shaft carrying that one of the idlers 45 meshing with gear 46 is adjustable in a curved slot 48 in the subframe or housing 49 (see Fig. 1). This permits of varying the size of the several 25 printing rolls 39, and the driving gears 46, and thereby accommodating them to bags of different lengths without varying their speed of revolution, which is always at the same number of revolutions per unit of 30 time as that of the main shaft A, or one half, or one third, or some other simple fraction of the same. The ratio of 1 to 1, is used when there is one design on each plate roll 39, and this is the case when 35 large bags are being printed. When the bags being made are so small that the plate rolls would be too small for convenience and good printing, if there were only one design on each roll, larger plate rolls are used, 40 but each carries two or three, or more, repetitions of the design for each bag. That is to say, there must be, of course, one impression printed for each cycle of the machine, which means for each complete revolution of main shaft A, so that if each printing plate roll 39 carries two reproductions of the design it should make but half a revolution for each cycle of the machine. If each plate roll carries three impressions, 45 50 then it should make only a third of a revolution for each cycle, and so on. This change in the relative number of revolutions of the printing rolls and main shaft A, per unit of time, is effected by changing gears 55 10 and 13 and reversible gears 11, 11^a. Such other changes in the common surface speed of feed roll 6 and platen and printing rolls as may be necessary for any reason, can be effected by changing gear 21 on shaft 20, 60 and adjusting the stub shaft 50 of idler 22, in slot 51, in subframe 49^a, to correspond. The proper degree of pressure between driving roll 6 and platen roll 7 is secured by the screw bolts 53, 53, (Figs. 12, 13 and 14) 65 bearing on the journal boxes 54, 54, for the

shaft of roll 6, which journal boxes are mounted in vertical slots in the subframe 49.

Folding mechanism.

70 After the strip of cloth 2 has been run through the printing mechanism as above described and then back over guide 9 and guide roller 9^a it goes down on a slight incline, as indicated by the broken line in Fig. 1, to the folding apparatus, shown in Figs. 1, 2, 15 to 17, which doubles the strip of cloth, forming a continuous fold longitudinally thereof.

This apparatus consists essentially of an 80 inclined floating frame 55 in the shape of an inverted isosceles triangle adjustable angularly about its apex as a center, and a pair of horizontal doubling or folding rolls 56 placed side by side below said triangular 85 frame, the meeting surfaces of which rolls are in the same vertical plane as is the perpendicular of the triangular frame 55, when the latter is in the mid-position of its angular adjustment about its apex. These rolls 90 56 are journaled in housings 79, 79, (Fig. 16) hung from cross-bars 80, 80 of main frame 52. The fabric 2 runs over the sides of this triangular frame and down between the doubling rolls 56, beneath it. From these 95 doubling rolls 56, the doubled, folded fabric runs horizontally (as indicated by the broken line Fig. 2), to and between the horizontal feed rolls 57, which are placed one over the other. Just before the fabric 100 reaches the face of the inverted triangular frame 55, (against which it is held by guide roller 58) and while it is under tension in passing from guide 9 and roller 9^a over roller 59 to and under roller 58, it passes between 105 guide fingers 60, 60, which are pivoted to swing laterally, in a vertical plane, and which, when swung to one side or the other by any lateral shifting of the fabric on rollers 58, 59, act through connecting mechanism 110 to send an electric current in one direction or the other through reversing electric motor 61, and so cause said motor to rotate in one direction or the other. This motion of the motor, transmitted through suitable connecting mechanism, swings the triangular frame 55 about its apex toward the side toward which the fabric 2 is creeping at that moment. Thus the upper portion of triangular frame 55, around which the edges of 115 web 2 are running, is kept always centered with reference said web so that one half of the web always runs over one side of the frame, and the other half runs over the other side, and the cloth is therefore evenly folded. This operation, repeated as occasion requires, 120 keeps the center line of the fabric 2 always running over the apex of the triangular frame 55, with the result that the line of fold of the fabric is always maintained co- 125 130

incident with its center line, and the two edges of the folded fabric will therefore always register one with the other and form a perfect bag when the folded sections are 5 sewed together by the sewing machines through which they run later.

The triangular frame 55 is supported near its apex and lower end by guide pin 62 passing loosely through curved slot 63 in 10 plate 64 on the frame, and screwed into horizontal bracket 65, carried by one of the housings 79. Slot 63 is curved on an arc struck from the apex of the triangular frame 55 as a center. This apex and center are in 15 the vertical plane of contact of the folding or doubling rolls 56. The frame 55 is supported at its upper end, adjacent to the base of the triangle, by two arc-shaped guide blocks 66, 66, (Fig. 17) bolted to castings 67, 20 67, (Figs. 16 and 17) mounted on cross bar 68 of main frame 52. These arc-shaped guide pieces are concentric with slot 63, having the apex of the triangular frame 55 as a common center. The frame 55 is guided 25 on them by little anti-friction rollers mounted on studs 69, 69, carried by the triangular frame.

The mechanism for swinging the frame 55 on the arc-shaped guides comprises the worm 30 70 (Figs. 15 and 16) on the shaft of motor 61, meshing with worm wheel 71 on threaded shaft 72, which shaft carries traveling nut 73, guided on rod 73, and operating bar 74 by means of a pin-and-slot connection 75 35 to horizontal arm 76, projecting from said bar (see Fig. 15). Bar 74 is supported by pivoted, parallel links 77, 77, swiveled at their other ends on an inclined bar 77^a, bolted at either end to brackets on main 40 frame 52, the lower one of which brackets is shown at 67^a in Figs. 15 and 16, while the upper one is shown at 67^b in Fig. 17^a. These parts form a parallel ruler mechanism, so that bar 74 is always parallel to bar 77^a. 45 Arm 76 is also connected to triangular frame 55 by pivoted link 78. Through these connections the motor 61, rotating screw shaft 72 in one direction or the other, moves parallel ruler bar 74 to the right or left (Figs. 50 15 and 17) and, through link 78, also swings triangular frame 55 slightly in a clockwise or counter-clockwise direction around its apex as a center.

The mechanism for controlling the direction of flow of current through reversing motor 61, by means of motion of guide fingers 60, comprises reversing contacts 95 and 94 (Figs. 15 and 15^b) to which the three wires 97, 98 and 98^a of the motor circuit 55 are connected, and means for moving these contacts operated by guide fingers 60. These guide fingers are pivoted on brackets 81, 81, (Figs. 15, 17^a and 17^b) horizontally adjustable on bar 82. This bar is movable 60 horizontally in bearing members 83, 83,

which have a screw-threaded mounting on the inclined screw-threaded shafts 84, 84. The upper ends of these shafts 84 are journaled in perforated lugs 85 on castings 67 (Fig. 16) and their lower ends are journalled in brackets 86 carried by one of the main frame cross-bars 80. In the bearing members 83, are also journaled the tension rolls 58 and 59 (see Fig. 17). Synchronous motions of revolution may be given to screw 75 shafts 84, 84, by bevel gearing connecting their upper ends with horizontal shaft 87 carrying hand-wheel 88 (Fig. 15). By turning this hand-wheel the tension rolls 58, 59 and bar 82 may be raised or lowered along 80 over the upper face of the inclined triangular frame 55 until roll 58 is over those points of the triangle's sides at which fabrics 2, of different widths, will begin to bend over the triangle's sides in the folding or doubling operation. At all positions of such adjustment, however, the bar 82 may be moved horizontally in bearing members 83 which support it, and will so move synchronously with any swinging motion of triangular 85 frame 55, because the depending arm 89, fast on bar 82 (Figs. 15, 16, 17, 17^a), carries pins 90, 90, which engage either side of parallel ruler bar 74, so forming therewith a sliding connection which is not interfered 90 with by any moving up and down of bar 82.

Any swinging movement of fingers 60, 60 on their pivots 91 (Figs. 17^a, 17^b) caused by the fabric 2 running to one side or the other, will be transmitted by connecting 100 rods 92 to bell-cranks 93, pivoted on brackets 96 (Fig. 15). These brackets are adjustably mounted on bar 82. One bell-crank carries the double finger contacts 95, between which swings the single finger contact 94 105 carried by the other bell-crank. In setting up this portion of the apparatus the bearing members 83 are screwed up or down by turning hand-wheel 88 until tension roll 58 is over that portion of triangular frame 55 110 which is as wide as the web of cloth 2, to be used; i. e., the link 78 is connected to the center strut 99 of frame 55 at one of the holes 100 therein (see Fig. 15) nearest roll 58; motor 61 is rotated until parallel 115 ruler bar 74 is moved into a position which will compensate for the angularity of link 78 and place triangular frame 55 in mid-position; brackets 81 are adjusted in such positions on bar 82 that fingers 60 will bear 120 on the edges of the cloth 2, when they hang vertically, and brackets 96 are so adjusted on bar 82, (or the connections of bell-cranks 92 to rods 92 are so adjusted by turning nuts 101), that the single contact finger 94 is 125 midway between double contact fingers 95. Then, when the machine is put in operation, the web of cloth 2 will normally run so that its center line will pass over the apex of the triangular frame 55, and its two half 130

sections 2^a, 2^a (Fig. 15^a) will be drawn in under the frame and doubled together between rolls 56, so that their edges exactly register one with the other as the folded web 2^b is 5 formed by rolls 56. If thereafter the web 2 begins to run to one side in the operation of the machine, say to the right looking at Fig. 15, it will swing the finger 60 at that side outwardly and, through the action of 10 its connecting rod 92 and bell-crank 93, swing contact finger 94 downward so that it touches the lower contact finger 95. This will send a current through wires 97 and 98 (Fig. 15^b) to motor 61, in a direction that 15 will rotate it in a direction to pull nut 73 to the right and, through the action of link 78, swing triangular frame 55 also to the right. Through the action of parallel ruler bar 74 and arm 89 the bar 82 will also 20 move to the right and the fingers 60, carried by the bar, will follow up the motion of frame 55 until it is again centered in the web 2. This recentering of frame 55 with 25 reference to the web 2 will allow the finger 60, which has been deflected, to return to vertical position under the action of weight 102 (Fig. 15) carried on its horizontal arm. The contact between fingers 94 and 95 will thereby be broken, motor 61 will stop, and 30 the parts will remain in their then existing position until another shifting of cloth web 2 swings one of the fingers 60 outwardly and either repeats the above described action or sets up a reverse rotation of motor 61, and 35 thereby establishes a new readjustment of frame 55.

The above described creeping action of the cloth is due to the fact that it is not always wound evenly on roll, consequently in 40 unwinding it may creep to one side or the other from time to time.

There is also considerable variation in the width of the cloth. Fingers 60 will follow this variation, moving in or out simultaneously, as the case may be, without causing any contact of fingers 94, 95, if the center line of the cloth runs true, because the fingers will rise and fall together. If the cloth did not vary in width, a much 50 simpler construction could be made to take care of the creeping action of the cloth and recenter frame 55 from time to time.

The circuits for the reversing motor 61 which automatically adjusts the triangular 55 frame 55 of the folding mechanism, are shown in diagram in Fig. 13^a. The field magnets have two windings 61^c and 61^b, which run in opposite directions. The supply circuit from the source of power P passes 60 through the armature 61^a and through both field coils 61^b and 61^c, when the single contact finger 94 is out of contact with both of the double fingers 95 (as indicated in Fig. 13^a) as the shunt circuits 97, 98 and 97, 98^a 65 are both open and the current runs through

both field coils 61^b and 61^c, which counteract one another, so that the armature 61^a does not rotate. When finger 94 touches one of the double fingers 95 (say the one closing shunt circuit 97, 98^a) the field coil 61^b is 70 short circuited and the other acts to rotate the armature 61^a in one direction. When the contact is made with the other finger 95, the field coil 61^c is short circuited and the other coil operates to rotate the armature in the 75 opposite direction.

Take-up mechanism.

The cloth 2 runs continuously through the printing mechanism and the folded web 2^b 80 is delivered through feed rolls 57 continuously at the same speed as that at which it runs through the printing mechanism. Beyond that point, however, its feed motion must be intermittent as it has to be stopped 85 while it is cut transversely into sections, the lengths of which correspond to a dimension of the completed bags. This cutting is done in the middle section of the machine shown at the lower portion of the plan view 90 (Fig. 28) and then these folded and cut sections must be later fed sideways along a line at right angles to their former line of travel through the cutter in order that they may go 95 through the sewing machines which will 95 sew them up into the form shown in Fig. 29. This sewing portion of the machine is shown in plan at the right hand portion of Fig. 28. To take up the slack of web 2^b, intermittently occurring during this change 100 from continuous to intermittent feed motion, the take-up apparatus shown in Figs. 1, 2 and 3, is employed. In this portion of the machine, the folded web 2^b delivered continuously from feed rolls 57, passes down 105 under take-up roll 107 journaled in boxes 108 sliding on vertical guide rods 109, and then runs up over guide roller 110. As the web 2^b is pulled over the roller 110 at double speed for a period of time and then stands 110 still for an equal period of rest, the take-up roll 107 rises and falls to take up the slack of the web intermittently formed by the constant feeding of the web from the rolls 57 during the periods of rest of roller 110. 115 To maintain the take-up roll 107 always exactly horizontal the boxes 108 are connected to an endless chain 111, which extends around six guide sheaves 112 (Figs. 1, 2 and 3). Two stops 109^a on rods 109, 120 limit the upward motion of the boxes 108.

Intermittent feeding mechanism.

From roller 110 the web passes to the first set of intermittently acting feed rolls 113, 125 and then horizontally to the second set 114. These two sets of feed rolls are rotated in unison by shaft 115 connected to the lower roll of each set by suitable gearing 113^a and 114^a. The intermittently exerted driving 130

power is applied to rolls 113 from gear 116 (Figs. 3, 5 and 18) which drives pinion 117 on the lower roll. The desired intermittent motion for this gear is primarily derived 5 from the oscillating crank 118 carried by cross shaft 119, and carrying a cam roller engaging the groove of barrel cam 120 on main shaft A. The cross-shaft 119 has a second shorter crank arm 119^a (Figs. 5 and 19) near one end, which crank arm is connected by link 121 to slide 122 (Fig. 3) moving in horizontal guides and carrying slotted floating lever 123, which is pivoted to said slide. The lower part of this lever 10 has a vertically adjustable fulcrum formed by bolt 124 engaging slot 125 in lever 123, and carried by block 126 movable in vertical guides on main frame 52 under control of screw shaft 127, which may be rotated by 15 hand wheel 128 through gearing 129 (Figs. 3, 5 and 8). The upper end of lever 123 has a pin-and-slot connection 130 to rack-bar 131 sliding in horizontal guides in main frame 52 and meshing with gear 132, which 20 has a loose sleeve-mounting on shaft 133, and carries with it friction dogs 134 mounted on radially projecting arms. These dogs engage the circumference of the flange on sleeve 135 (Fig. 18) journaled in main frame 25 52 and carrying bevel gear 136 on its outer end. The mechanism so far as described changes the reciprocating motion of oscillating crank 118 into an intermittent, one-way rotation of bevel gear 136. This latter motion is transmitted at half speed to 30 gear 116 by means of beveled pinions 137, carried by lugs 139 on gear 116, and floating between intermittently rotating bevel gear 136 and stationary bevel gear 138 which is 35 fast on shaft 133. (Figs. 18 and 19). By turning handwheel 128 and moving shifting fulcrum bolt 124 up or down, the throw of rack bar 131 will be lengthened or shortened and the extent of each intermittent rotation of rolls 113 and 114 thereby adjusted 40 accordingly to feed cloth sections of different lengths forward to the shears. The cloth passing through these rolls on its way to the cutting or shearing mechanism, to be 45 next described, has printed matter placed on it by the printing rolls 39, 39, in a series of repeated patterns. The shears should cut the cloth always at a given point between these patterns so that they may be properly 50 located on the finished bag. The cloth, however, sometimes stretches more or less, or slips on the various feed rolls, in its long journey from roll 1 to the feed rolls 113. To readjust the position of the cloth with 55 reference to the shears without stopping the machine, the feeding action of the rolls 113 and 114 may be set forward or backward the necessary amount by rotating normally stationary bevel gear 138 which, as before 60 stated, is fast on shaft 133. This adjusting 65

motion can be transmitted to rolls 113 and 114 from handwheel 140 (Figs. 5 and 21) through shaft 141 and gearing 142. This operation of adjusting the feed rolls 113 and 114 can be repeated as often as the operator 70 observes the printed matter getting out of center on the cut sections of the cloth. If the operator sees that the printed matter is running two inches ahead of its proper position on the bag sections, he will twist 75 handwheel 140 enough to turn gear 138 backward sufficiently to set rolls 113 and 114 back a circumferential distance of two inches, thus re-centering the designs printed 80 on web 2^b with reference to the web cutting apparatus.

Shearing mechanism.

The mechanism for cutting the web of cloth into sections is illustrated in Figs. 3, 5, 8, 20, 21 and 25. It consists of the horizontal, yieldingly mounted blade 143 and the vertically reciprocating, obliquely edged blade 144. The latter is mounted on vertical links 145, 145 (Fig. 20), pivoted to 90 crossed cam levers 146, 146, the other ends of which are pivoted at 147, 147, to the main frame 52. These levers carry a common cam roller 148 (Fig. 3) engaging the cam groove in disc 149 on main shaft A. 95 The pin carrying this cam roller is fast on one lever 146 and passes through a slightly elongated hole in the other, so as to allow the levers to swing on pivots 147 slightly, as required. The knife or shear blade 144 can swing in an endwise direction, being supported by pivoted links 145, as above described, and is given an oblique motion to the left (looking at Fig. 20) as it descends by reason of the anti-friction rollers 150, 100 carried by it, running along the inclined guides 151 which are rigid on the knife housing 144^a, mounted on main frame 52. The lower shear-blade 143 has a slight amount of horizontal play, being held to its 105 support 152 (Figs. 3 and 5) by screws 153 passing through slots 154 (Figs. 5 and 8). It is forced against vertical blade 144 by spring pressed levers 155 (Figs. 5 and 8) 110 which are pivoted on the main frame and bear against lugs 156 carried by strips 157 which are connected to blade 143 at their forward ends. At their rear ends these strips carry adjustable stops 158 (Figs. 3, 4 and 5) which strike against a cross-bar of 115 the main frame and may be adjusted to limit the forward movement of the blade. The shear blade 144 also has a downwardly extending lug 144^b (Figs. 20 and 21) 120 at its lower end, which prevents the other blade 143 being pushed under it, if stops 158 are not properly adjusted. The effect of all this described mechanism is to cause the vertical blade 144 to make a drawing 125 cut on the folded cloth web 2^b along the 130

edge of the horizontal blade, which is held closely but yieldingly in contact with the vertical blade during the shearing operation.

To prevent the cut edge of the advancing cloth falling down in the space which must be left for the passage of the vertical blade below the plane of travel of the cloth, the hinged bridge 159 is held up by springs 160 (Figs. 3 and 5) to close this space as soon as the shear blade rises.

Feeding mechanism for cut sections.

After a predetermined length of the folded web 2^b has been fed through the shears by the intermittently rotating feed rolls 114, the vertical shear-blade descends and shears off such section, as before described. During this shearing action the feed rolls 113 and 114 are stationary and a set of spring fingers 161 (Fig. 3) is moved up to grasp the forward end of the cut section of cloth and draw it onward and out of the way of the next forward motion of web 2^b which will occur as soon as the shears are opened. These fingers 161 are pivoted to slides 171, which rest on horizontal guides 162 (Figs. 25^a to 25^d) and are reciprocated by the motion of lever 118, the end of which is connected by link 163 (Figs. 3, 4 and 5) to cross-bar 163^a (Figs. 3 and 5) swinging on frame 164 which is pivoted in main frame 52 at 165. The upper ends of frame 164, are connected by short links 166 to cross-head bar 167, which is carried by bearing blocks 168 (Figs. 5 and 19) sliding in horizontal guides 169 in the main frame 52. From cross-head 167 rods 170 extend to the slides 171 (Figs. 25^a to 25^d) which carry fingers 161. Slides 171 are mounted on and between horizontal guides 162. The fingers 161 are pivoted to the slides at 173 and are normally forced down on the slides, in a position to grip the cloth, by springs 174 as shown in full lines in Figs. 3, 4 and 25^a. The lower edges of the fingers have trigger projections 175 which lie in notches 176 of strips 177 which are loosely mounted and movable endwise in slides 171, when the motion of said strips toward the shears is arrested by their striking stops 178 (Fig. 25^a). These stops are carried by strips 172 which are adjustable with reference to guides 162 by reason of the slot and set screw connections 179 between them. When slides 171, and the fingers carried thereby, are moved to the other limit of their motion, indicated in dotted lines in Fig. 25^a, and in full lines in Fig. 25, and the other ends of strips 177 strike the adjustable stops 180, fingers 161 are opened by the action of said strips on triggers 175, as indicated in the dotted line position. Strips 177 have frictional bearing in slides 171 sufficient to cause said strips to travel back and forth with the slides until they strike stops 178 or 180.

The fingers 161 and the reduced, or fin-like portions 171^a of slides 171 travel in slots 181 (Figs. 8 and 25^c) in the fixed table 182, along which the folded bag sections move from the shears, and also through slots 183 in the vertically movable table sections 184 onto which the bag sections are pulled by fingers 161 (Fig. 8). When in proper position on table 184 the bag sections are stopped and stripped from the fingers 161 by stop 185, (Fig. 8, 25 and 25^a), hinged to brackets 220, by pivot shaft 185^a.

The main function of movable table section 184 is to afford means for transferring the cut sections of fabric from control of the hereinbefore described feeding mechanism to the control of another feeding mechanism operating along a line extending at right angles to the first mentioned one, so as to pass the sections through the sewing machines with their folded ends first, in order that these machines may sew the opposite edges of each folded section together, thereby forming bags having the folds of the cloth at their bottoms.

Transfer mechanism.

The transfer mechanism comprises the table 184 which is vertically movable on slides 186, (Figs. 4, 6 and 10) running in guides on main frame 52, and which slides are raised and lowered by links 187 pivoted at their lower ends to twin cam levers 188 (Figs. 6 and 26) which are fulcrumed to the main frame at 189 and are vibrated by a common cam roller 190, which engages a cam slot in disc 191 keyed to main shaft A. When the circular portion 191^a of this cam slot engages the cam roller, table 184 is in its lowest position on a level with fixed table 182, as shown in Fig. 4, and during this period the cut section of cloth is pulled on to this table 184 by fingers 161, as previously described. Next the cam portion 191^b, of greatest radius, engages the cam roller and lifts table 184 to its highest position on a level with sewing table 204, as shown in Fig. 26, impaling the cloth section on the pins 200^a (Figs. 22, 23 and 26^a) of the sprocket chains 200, the lower strands of which are constantly traveling to the right (looking at Fig. 26^a). The ends of these pins move in shallow cross grooves 184^a (Fig. 27) in table 184 while it is in this highest position. After the front end of the bag section has been pulled by the pin-chains onto the sewing table 204 the cam roller 190 runs off cam portion 191^b onto the intermediate portion 191^c (Fig. 26) which lowers table 184 slightly, through a distance equal to the thickness of fork 192, (Figs. 6, 26 and 27) which reciprocates horizontally in grooves 204^a of table 204, and this fork is shot out under the bag section, clearing table 184 because of the

above described slight drop of the latter, the parts being in the position shown in Fig. 26. The fork then holds the cloth up against the chains 200 and in engagement with pins 5 200^a after the cam roller has run back onto section 191^a of the cam groove and table 184 is dropped to its lowest position. While the table is in its highest and intermediate 10 positions the spring fingers 161 travel back under it to grasp the next bag portion which is coming through the shears as before described. The fork 192 travels to the right (Fig. 26) with the bag section 15 after stripping it from table 184. This to and fro motion is given to the fork 192 by slides 193 (Figs. 6, 8, 22 and 26) to which it is attached by means of carriage 193^b mounted on cross-bar 193^c which connects slides 193 which are reciprocated on 20 horizontal guides 193^a by levers 194 pivoted to the main frame by shaft 195 and vibrated by connecting rod 196. These levers have pin and slot connections to slides 193 as shown in Fig. 6. The other slotted end 25 197 of the connecting rod 196 is guided on shaft, A (Fig. 26) and carries a cam roller 198 which engages the heart shaped cam groove 199 in the face of disc 191 opposite to that having cam groove 191^a (Figs. 10 and 26). The fingers of fork 192 are slotted throughout as shown at 192^a in Fig. 27, so as to straddle the pins 200^a, and consequently when they are shot out over the table 184 they press the bag section firmly up into 30 engagement with the pins 200^a and positively strip the cloth from the surface of 35 table 184.

The pin-sprocket chains 200, run around sprocket wheels on shafts 201 and 201^a, 40 (Figs. 26 and 26^a) and between vertical chain guides 202 which are slotted at their bottoms to permit the pins 200^a to project through and impale the bag sections, numeral 202^a (Fig. 26^a) indicates a removable 45 section of one guide 202 to give access to the chain. The left hand sprocket, on shaft 201 (Fig. 26^a), is an idler and is adjustable in the slots 201^b in guides 202, to take up the slack of the chains. The chains are 50 driven at a uniform speed in a counter-clockwise direction by shaft 201^a which is journaled in housings 201^c (Figs. 9 and 24) on main frame 52, and is rotated by helical gear 203^b driven by helical gear 203^c on 55 vertical jack shaft 203, which is driven by helical gearing 203^a from shaft D (Figs. 7, 9, 11 and 24).

The front ends of chain guides 202 are supported by four brackets 220, two of 60 which are carried by slides 210 (Figs. 4, 6, 7 and 8), movable on main frame 52, while the other two are mounted on the main frame itself. The two right hand brackets 220 (looking at Fig. 4) as well as

the outboard end supports 205 for spring finger guides 162, (Figs. 4 and 25), are movable horizontally at right angles to the line of travel of the pin sprocket chains, being mounted on these slides 210. The right hand sewing mechanism (looking at Fig. 23), and these last mentioned brackets are moved by turning shaft 206 carrying pinions 207 (Figs. 23, 8, 9 and 10), which transmit motion through idler gears 208 to racks 209 on the under sides of slides 210 carrying two of the brackets 220 as as before stated, and of slide 227 (Fig. 23) which carries one sewing machine with its driving and thread cutting mechanism and one member of each of the two other sets of brackets 228 (Figs. 7, 9 and 23) which support the middle portions of chain guides 202. The outer end of shaft 206 is squared (see Fig. 10) to engage a hand crank for turning it. This permits the two pin sprocket chains and the two sewing machines and their thread-cutting mechanisms to be spaced apart properly to handle bags of different widths. The adjustment of these parts also adjusts longitudinally the position of the spring finger guides 162 so that the zone of travel of fingers 161 may approach nearer to the shears 143, 144, to grasp a short bag-section and drop it at the proper point on table 184 to center it with reference to pin-chains 200 when the latter are adjusted close together to handle a small bag, or pick it up at a point more distant from the shears and carry it further along to similarly center it when the chains are placed farther apart to handle a large bag.

The inboard ends of the guides 162 are supported on slides 211 (Figs. 25, 25^a) which are adjustable on horizontal rods 212 105 to accommodate this adjustment of the bag-sewing mechanism and pin-chain feed mechanism. The limits of motion of spring fingers 161 are adjusted to correspond to the adjustment of guides 162 above described, by moving their connecting rods 170 in the split clamps 213 of cross-head 110 167 (see Figs. 3, 5 and 19).

To positively move the rear end of adjustable chain guide 202, which is supported on shaft 201^a, a rack bar 214 (Figs. 4 and 23) is fastened to this movable chain guide 202 and extends through the stationary chain guide 202 to mesh with pinion 215, on idler shaft 216 (Figs. 4, 9 and 23), which carries pinion 215^a on its other end meshing with a similar rackbar 214^a (Figs. 7, 9 and 24) which is also fast on the movable chain guide 202. Shaft 216 is journaled in brackets 217 (Figs. 9, 23 and 24) 120 on main frame 52. The sprockets for this end of the chains 200 are mounted on sleeves keyed to shaft 201^a, (see Fig. 24^a) 125

and the right hand sleeve is movable along the keyway in the shaft 201^a to allow for the adjustment of movable chain guide 202.

Shaft 201^a is driven through the friction clutch shown in Figs. 24^a and 24^b, in order that the same may slip and so save the pins 200^a from being broken by the cloth if it gets caught anywhere along its line of travel. This clutch consists of spring 10 pressed levers 218 pivoted on the driving gear 203^b on shaft 201^a, and acting as a pair of friction jaws to grasp between them the elliptical collar 219 keyed on the shaft. The friction between collar 219 and spring 15 pressed levers 218 will be greatest when the major axis of the ellipse is crossways of the levers as shown in Fig. 24^b. Consequently the parts will come to relative rest in, and remain in, this position during the 20 normal operation of the machine. If the cloth is caught in the sewing machine or elsewhere, the friction of levers 218 on collar 219 will be overcome and gear 203^a will continue to rotate while shaft 201^a stands 25 still, and consequently the pin-sprocket chains will cease to move until the trouble is remedied.

The vertically movable table 184 is made in two sections which overlap, as best 30 shown in Fig. 25^a, which sections are separately supported by two separate rows of pillars 223 and 223^a. Pillars 223^a are adjustable laterally (see Fig. 4) on sub-table 224 to correspond to adjustments of the 35 movable pin sprocket chain, etc., being fastened thereon by bolts 225, passing through slots in said table which is supported by slides 186. When these bolts are loosened the row of pillars 223^a, may be adjusted to 40 accommodate bags of different dimensions in unison with the slides 210 which carry the movable brackets 220, supporting one of the pin-sprocket chain guides 202. This 45 synchronous adjustment is effected by anti-friction rollers 230, carried on either end of the row of pillars 223^a, and running in vertically slotted lugs 226 on the slides 210 (Figs. 4 and 8). These slides 210 are moved 50 on slotted guides 210^a when being adjusted, and are clamped in each position of adjustment by bolts 210^b, (Figs. 6 and 8).

To prevent any of the bags falling down after passing the end of the sewing table 204, as they might not be held securely by 55 mere friction on pins 200^a, I provide short gripping sprocket chains 221 (Figs. 7 and 9) which are driven by sprockets 222 (Fig. 24^a) on shaft 201^a, and which run over idler sprockets 222^a carried on stub shafts 222^b 60 mounted in chain guides 202 (Fig. 26^a). The lower strands of these sprocket chains rest by gravity on the edges of the bags and hold them down on strips 204^a supported beneath the chains 221 by C-shaped brackets 229 (see Figs. 24 and 26^a) which are 65

bolted to chain guides 202. This prevents the bag falling away from pin sprocket chains 200 and prematurely dropping off the pins 200^a. This action of the gripping chains 221 causes the bags to travel onward 70 under control of pin sprocket chains 200 until they are stripped off by the delivery fly, hereafter to be described.

Sewing mechanism.

75

As before described the bag sections are pulled over the sewing table 204, folded end first, by pin-sprocket chains 200 at a uniform rate of speed. If the bag is to have a seamless bottom, two sewing machines 231, and 231^a, (Fig. 9) are placed on either side of the path of the bag sections over the sewing table and their opposite edges are sewed, thus producing the article shown in Fig. 29, which is turned inside out to form the completed bag of Fig. 30. These machines are set in recesses 232, in table 204, (Figs. 27 and 27^a). They are set on slides 233, and 233^a, (Figs. 7, 23 and 9) so that either sewing machine and its gearing and thread-cutting attachments may be taken out as a unit, for repairs. The driving shaft 234 (Figs. 7, 9 and 23) for the machines is journaled in a housing on slide 233^a and carries a herring-bone pinion 235 meshing with a similar idler gear 236 which is driven by gear 237 on horizontal shaft 238 (Fig. 22) carrying pinion 239 which is driven by helical gear 240 loosely mounted on shaft D and driven by clutch 240^a. (Figs. 7 and 11). 95 Each sewing machine carries a sleeve 241 or 241^a, which telescopes over the adjacent end of shaft 234 and has a slot and key connection thereto. The sleeve 241 of sewing machine 231 is made long, as shown in Fig. 23, to allow the sewing machine to be moved outward with the corresponding chain guide 202, when larger bags are to be sewed. Each sleeve is journaled in a housing on its slide 233 or 233^a and is prevented 100 from moving outward axially by collar 249 or 249^a, placed on the inner side of the housing. On the other side of the housing the gear 248 is loosely mounted on the sleeve but normally locked thereto by the following mechanism: Sleeve 241 has one or more radial openings through which project radial pins or dogs 243 carried by ring 244 located inside the sleeve in an annular recess therein, the internal diameter of the ring 105 244 being large enough to permit shaft 234 to pass through it when slide 233 is moved inward. The pins 243 project beyond the outer surface of sleeve 241 and (as shown in Fig. 23) are engaged by slots in the inner end of hub 245, also loosely mounted on sleeve 241, when said hub is forced inward by spring 247 placed inside the hub and confined between a shoulder at the inner end of the bore of the hub and the collar 242 110

pinned on the outer end of the sleeve 241. Hub 245 is locked to gear 248 by pins 246 set in the inner face of the hub and entering holes in gear 248. These pins are long enough so that they cannot be disengaged from the holes in gear 248 by any endwise movement of hub 245 permitted by spring 247, because the coils of the spring will close on one another and form a stop to the outward movement of hub 245 before the pins 246 are freed from gear 248. The possible movement of the hub is however sufficient to free it from radial dogs 243 and consequently from any positive engagement with sleeve 241. Consequently rotation of shaft 234 is normally transmitted through sleeve 241 and spring hub 245 to gear 248, and from that to pinions 250 and 250^a (Figs. 7, 23 and 9) on the shafts of sewing machines 231 and 231^a. If the operator wishes to disconnect that sewing machine he pulls out hub 245, compressing spring 247 until the dogs 243 are freed from the recesses in the hub. The hub and gear 248 will then stop turning, the sleeve 241 having no engagement therewith. Pins 246, however, are not entirely withdrawn from engagement with gear 248, and the latter may be turned by hand (through manipulation of hub 245) to operate the sewing machine slowly, to free the needle from the cloth, or for any other purpose. When the hub is released, spring 247 forces it back into engagement with ring dogs 243, and the apparatus can be power driven again. The mechanism for driving the other sewing machine, 231^a, is the same, except that the sleeve 241^a is shorter. If, for any reason, bags are desired having a seam across the bottom and up one side, the fold of the cloth forming the other side of the bag, as shown in Fig. 31, sewing machine 231, is taken out of the position indicated in Fig. 9 and installed in the position shown in dotted lines in Fig. 28, where it sews together the edges of the folded web 2^b before the latter is cut up into sections. The rearward end of each section is later sewed up by machine 231^a. Any convenient driving gear from main shaft A may be employed to drive the machine 231^a in this last described position.

Thread-cutting mechanism.

The bags formed by the sewing operation are connected together in a chain by the threads forming the seams. To cut the threads and separate the bags I employ rotary disc knives, as 254, 254^a (Figs. 23, and 23^e) journaled in housings on slides 233, 233^a. As the two sets of mechanism are duplicates I will describe the one cooperating with knife 254, which is driven by helical gearing 253 from shaft 252, which, at its other end, carries pinion 251 (Fig. 7) meshing with clutch gear 248. The knife

discs therefore run continuously. To force the thread down on these knife discs I employ double star-shaped thread-deflectors such as 255 (Figs. 23, 23^a and 23^e) journaled one above each knife disc, and revolved intermittently a fraction of a revolution so that those ones of the double arms which happen to be in operative position at the moment the division line between two successive bags comes under them will swing down on either side of the knife disc below and push the thread against the revolving edge thereof. A stop pinion 256 on the shaft of each thread deflector is engaged by a stop pawl 257 (Fig. 23) to prevent its overrunning or running backward.

The actuating mechanism for 255 must be intermittent, operating once for each bag-making cycle, and it must operate very quickly. The mechanism here to be described and illustrated in Figs. 23 to 23^e has swinging bar 263 as its motive power. This bar is hung on parallel links 263^a and connected by rods 262 and links 261 to cranks 260 on ratchet clutches 259 which drive the star wheels 255 through gearing 258. When bar 263 drops, the clutch 259 will transmit the consequent quick vibration of crank 260 through clutch and gear to 255, and quickly swing it through a quarter revolution. When bar 263 rises ratchet clutch 259 slips backward, since backward rotation of 258 is prevented by dog 257, engaging stop pin 256.

Swinging bar 263 is raised and dropped by notched slide 264, traveling on horizontal guide 265 and being moved by tappet lever 267, (Figs. 23^b and 26) striking adjustable tappet bolts 266 on the slide. Lever 267 is pivoted at 268 and oscillated by connecting rod 269 pivoted at its other end to vibrating lever 270, which carries cam roller 271 (Figs. 4 and 10) engaging a cam groove in disc 272. This disc (Figs. 4, 6 and 10) is adjustably mounted by pin and curved slot connection 273 on disc 274, fast on main shaft A. During motion of slide 264 to the right, (Fig. 23^b) bar 263 is supported by dog 277, while slide 264 moves under it until the laterally projecting lug 276 on the slide (Fig. 23^a), knocks out the dog into the position shown in Fig. 23^c, and so drops bar 263 onto the rest 275 also formed on slide 264. The return motion of 264 drops bar 263 into notch 278 (Fig. 23^b) thereby operating the thread cutter through the connections above described. Bar 263 is lifted again and reset by the inclined surface of the slide 264 being drawn under it during the return motion until the bar rests on elevated face 279 which is high enough to transfer it back to dog 277, when the passing lug 280 Fig. 23^a, also formed on the slide, has engaged trigger 281 on the dog (indicated in dotted lines in Fig. 23^c), and swung

it into its original position, shown in Fig. 23^b.

Delivery mechanism.

5 When the completed bags are pulled off the sewing table 204 and are supported only at their edges on strips 204^a (Figs. 27^a and 24) the slotted fly-sticks 286 (Figs. 7^a and 27^a) are slid over the bags, along either side 10 of the chain guides 202, and then allowed to fall into the position shown in Fig. 7^a. This pulls the bag away from gripping chains 221 and pins 200^a and allows them to drop on to delivery belt 291 beneath. 15 Fly-sticks 286 are mounted on cross shaft 287 carried by slides 285 reciprocated on horizontal guides 285^b, (Figs. 7, 11 and 26) by connecting rod 282, which connecting rod is pivoted at one end to tappet lever 267 and at the other to swinging frame 283 20 fast on horizontal shaft 284. This shaft is journaled in main frame 52, and the swinging frame 283 is connected at its upper ends to slides 285^a by short links 285. (See Fig. 24.)

25 When shaft 287 is moved to the right (looking at Figs. 7 and 7^a) by the above described mechanism, the trailing crank 288 mounted on it is forced down by the inclined surface of latch-slot 289, in which runs a friction roller carried by the crank 288. This retracts and raises fly-sticks 286 into the position shown in Fig. 26. When they are driven forward over the approaching bag by the reverse movement of swinging frame 283 the friction roller on trailing crank 288 runs under spring latch 290 and the fly sticks are held up in horizontal position so that they pass over the approaching bag. When the roller runs off the left hand end of the spring latch the fly sticks drop by their own weight as before described, the roller is raised so that it will pass over the latch 290 when the fly-sticks are retracted, and the cycle is completed.

Counting mechanism.

Delivery belt 291 supported by table 293, which rests on cross rods 293^a and 293^b (Figs. 7, 9 and 11) stands still until a given number of bags have been deposited on it by the fly-sticks (say one hundred) and then moves far enough to carry that pile of bags partly out from under the sticks. 50 The mechanism employed to effect this intermittent motion of the belt, which runs over idler pulley 292^a adjusted by take up screws 292^b (Fig. 11) and over driving pulley 292, is driven by crank 294 on shaft 284 55 of swinging frame 283 (see Fig. 24). The pin 295 on crank 294 engages the vertically slotted member 296 which is adjustably mounted on horizontal rack bar 297, which slides in guide 298 (Figs. 7, 11 and 24^c). 60 The rack on this bar meshes with pinion 65

299, which is loose on the shaft of drive roller 292 of the belt. 300 is a spring ratchet-clutch the driving member of which is keyed to the shaft of the roller 292 and which will give said roller and shaft about 70 one revolution for every left hand stroke of rack bar 297, (looking at Fig. 11), if the clutch is in engagement. Normally the clutch is out of engagement, however, its operating lever 301, pivoted at 302, being 75 held in a position to open the clutch in spite of the pressure of the clutch-spring tending to close it. The lever is held in this position because its trip pin 303 (Figs. 24, 24^c) bears on the face of an idling ratchet 80 wheel 304 journaled on the main frame 52. This ratchet wheel is moved one or more teeth at every cycle of the machine operation by pawl 306 carried by reciprocating rack bars 297. Once in each revolution of 85 the ratchet wheel the trip pin 303 drops into slot 305 in the wheel face (Figs. 24 and 24^c) and clutch 300 is thereupon by the action of its spring, thrown into engagement. This gives the belt 291 its intermittent 90 feeding movement. Pin 303 is pulled out of slot 305 on the return motion of the rack bar 297 because the beveled trip finger 307 thereon (Fig. 11) wedges lever 301 outward and resets the pin 303 back on the 95 face of the turning ratchet wheel. This also opens the clutch, of course, and leaves the belt at rest until the ratchet wheel 304 has made another revolution.

The pawl 306 is tripped from engagement 100 with the ratchet wheel 304 by its tail lug striking adjustable trip 308, (Fig. 7). This trip member is adjustable through its set screw and slot mounting 309 which may be set so that the pawl will be tripped out of 105 engagement with the teeth of ratchet wheel 304 after the latter has been turned a space of one tooth, or two teeth, or more, as may be desired. This will cause delivery belt 291 to move more or less frequently and so 110 determines the number of bags which will be accumulated in each pile on the belt.

The general operation of the machine shown in the drawings is as follows: The electric motor B is arranged to drive the sewing machines at the maximum safe speed. The pin-sprocket chains are geared to feed the bag sections through the sewing machines at a speed of an inch travel for every five stitches. A roll of fabric 1 of the proper width is installed in the machine and the free end of the web threaded through the printing, folding and take-up mechanism, to and through feed rolls 114. The guide and tension rolls 58, 59, the guide fingers 60 120 and their associated apparatus, are moved up or down by turning hand-wheel 83 until roll 58 is slightly above the points on the edges of the V-shaped frame 55 at which the fabric begins to bend down to the fold. 125

ing rolls 56. The change gears in the printing mechanism are adjusted to give the proper speed of travel to the fabric and produce one impression for each revolution of 5 main shaft A. The throw of slotted lever 123 is adjusted so as to give the intermittent feed rolls 113 and 114 the required amount of rotation to feed forward a bag-section of the predetermined width in each cycle of operation. 10 The change gears F are adjusted so that the speed of shaft D relative to that of main shaft A will be such as will give the shaft A one revolution for every such number of revolutions of shaft D, as will cause 15 the table 184 to feed the bag-sections to the pin-sprocket chains at a rate such as will leave a space of about an inch between successive sections. The movable chain guide 202, its associated sewing machine and other 20 connected apparatus, are adjusted to handle bags of the predetermined width, and the zone of travel of the spring fingers 161 is adjusted accordingly. The trip 308 for the 25 counting mechanism is set to deliver the predetermined number of bags in each bundle, and the machine can then be started into operation.

The printed and folded fabric is either 30 sewed along one edge, if the sewing machine 281 is located as shown in Fig. 28, and the rear end of each bag section (which becomes the left-hand side after the section has passed the transfer table 184) is sewed by machine 231^a, or it is sewed along both 35 ends by the two machines 231 and 231^a while being fed sideways between them, if they are in the positions shown in Fig. 9.

After the folded cloth is cut into sections 40 by the shears 143, 144, each section is pulled onto transfer table 184 by spring fingers 161 and butts up against swinging stop 185, which is adjustable with the movable pin-sprocket chain guide 202 and associated parts. As table 184 rises this swinging stop 45 pushes the bag-section backward slightly to ensure its being accurately placed on the table to register with the sewing machines when fed to them by the pin-sprocket chains. If there were no "placing" apparatus, having this or equivalent mode of operation, the 50 bag sections would not all stop in the same position on the table 184 and the seams would not be evenly spaced from the edges of the bag after these were sewed together.

55 Stop 185, which is a little beyond the proper position of the forward end of the bag section on table 184 when said table is in its lower position and swings up with the raising of the table, to get its final position, 60 gives an accurate positioning of the bag-section even if the spring fingers 161 have originally left it in a location on the table which was not quite up to the edge of said stop in the lowest positions of the stop and 65 table.

After the fingers 161 have left the bag section on table 184, said table rises, as above described, and impales the bag section on the travelling pins 200^a, which begin to move it toward the sewing mechanism. The 70 spring fingers 161 travel back under the raised table to grasp the next following bag section and, before they return, table 184 has dropped down so that it is ready to receive the next section fed to it by fingers 161. 75

As soon as the edge of the bag section has moved onto the sewing table 204 the table 184 drops slightly and the forks 192 are shot out over the table and under the bag section, 80 ensuring its continued engagement by the pin-sprocket chains after table 184 has dropped down to receive the next section.

The pin-sprocket chains drag the bag section out over the sewing table and through the 85 sewing machines. When the successive bag-sections leave the sewing machines they are connected together, end to end, by the thread used in sewing their seams. As the dividing line between each two successive bag-sections comes opposite the rotating thread cutting knives 254, 254^a, the threads are forced down on the knives by the arms of the thread deflectors 255, which are thrown quickly down by the swinging bar 268 dropping off the 90 rest 275 on notched slide 264. Thereafter 95 the separate sections are fed onward still further by the pin-sprocket chains until the falling fly-sticks 286 strip them from the pins 200^a and deposit them on the delivery belt 291.

When the pile of bags on the belt 100 has grown to the predetermined number, say 100, the belt is moved by the rack bar 298 and pinion 299, operating through clutch 300, far enough to carry the pile of bags 105 partly out from under the fly-sticks. Preferably this travel of the belt is adjusted so that the piles of bags will overlap one another as they are formed, as shown in Fig. 26. This enables the operator to easily pick 110 up and remove the series of completed piles from time to time.

The fly-sticks 286 may be timed by adjusting the cam disc 272 angularly on its supporting disk 274, which is fast on shaft A. The cam disc carries threaded pins engaging curved slots in the fixed disc, as shown at 273, in Fig. 6. This enables the two discs to be clamped together in various relative positions.

The above described adjustment of cam disc 272 also affects the timing of the thread-cutters 255, but the ultimate timing of these thread-cutters is effected by adjusting the tappets 266 on notched slide 264 (see Figs. 115 23^b and 26).

Other minor adjustments to secure accurate cooperation of the various elements of the machine can be made by means of the threaded or slotted connections shown at 120 various points in the drawings. 125 130

Of course various changes could be made in the particular details of construction and types of machine elements and gearing shown in the drawings, without departing 5 from the principle of the invention which is capable of various different embodiments.

Having described my invention, I claim:

1. In a bag-making machine of the type having sewing machines, means for driving 10 said sewing machines and for feeding sections of cloth to said machines at a substantially uniform surface speed adjusted according to the maximum speed of said sewing machines, and apparatus for cutting the 15 cloth into uniform sections of greater or less length, the combination, with the above recited elements, of a printing apparatus comprising a platen roll and gearing from the driving means for driving said platen roll 20 at a surface speed corresponding to the size of the bags to be made, a series of cooperating interchangeable plate rolls of different diameters corresponding to different sizes of bag sections, bearings for said plate rolls 25 adjustable radially of the platen roll, and change gearing between said driving means and the particular plate roll in use, whereby one printing operation may be effected for each bag section of whatever size cut and fed 30 through the machine by employing a plate roll of corresponding diameter and adjusting the change gear to produce one revolution of said plate roll for each bag section.

2. In a bag making machine of the type 35 wherein a cutting apparatus and an intermittently acting mechanism for feeding the cloth to the cutting apparatus are employed, the intermittent action of the feeding mechanism being timed to correspond with 40 the operation of the cutting apparatus but the surface speed of the feeding mechanism being separately adjustable to conform to bags of different sizes, the combination, with said above recited elements, of a printing mechanism operating on the cloth before it 45 reaches said feeding mechanism, said printing mechanism comprising a platen roll, gearing for driving said platen roll at a surface speed corresponding to the different 50 surface speeds of the feeding mechanism, a series of interchangeable plate rolls of different diameters corresponding to the various 55 amplitudes of the intermittent feeding operation, and gearing for driving any particular plate roll in use at the same surface speed as that of the platen roll and of said feeding mechanism.

3. A combination such as set forth in 60 claim 2, in which the intermittently acting cloth feeding mechanism comprises a set of feed rolls, a driving gear, radially disposed bevel pinions journaled in said gear, a driven bevel gear meshing with said pinions on one side thereof, a normally stationary bevel gear meshing with said pin-

ions on the other side thereof, and manually controlled means for circumferentially adjusting said normally stationary bevel gear.

4. In an adjustable feeding mechanism for bag making machines and the like, the 70 combination of feeding rolls and a train of mechanism for driving said rolls comprising a member and means for driving it at a predetermined speed, a normally stationary member, a rotatable third member 75 driven by the combined action of the first two members and geared to the rolls, and means for changing the position of the normally stationary member, whereby while the third member is normally rotated at a given rate of speed, said speed may be temporarily varied by moving the normally stationary member in one direction or the other.

5. A reciprocating gripper mechanism for use in bag machines and the like, which comprises in combination, a stationary guide bar, a carriage adapted to slide thereon, means for reciprocating said carriage, a finger pivoted on the carriage and adapted to press upon the surface thereof, a spring connected to the carriage and to said finger to produce such pressure, a notched slide mounted in the carriage in contact with the finger, a trigger on the finger adapted to drop into the notch on the slide to permit the finger to close on the carriage under the action of the spring but to hold the finger away from the carriage when resting on the full-faced portion of the slide, and stationary stops located near each end of the zone of travel of the carriage and in line with either end of the slide, whereby when the carriage approaches the limit of its forward travel the slide strikes and is arrested by one stop so that the completion of the forward carriage movement pushes the finger over the slide until the trigger drops into the notch therein, permitting the spring to swing the end of the finger against the carriage surface, and when the carriage approaches the other limit of its travel the other stop strikes the other end of the slide, arresting its movement so that the completion of the carriage movement in that direction pushes the trigger out of the notch and swings the finger away from the carriage surface.

6. In a bag making machine of the type 120 wherein a web of cloth is folded longitudinally, the folded web fed longitudinally to a cutting apparatus and cut into sections, and said sections are fed laterally to a sewing machine, the combination with said above recited elements of a slotted vertically movable table through the slots of which fingers may pass to pull said section onto the table when it is in its lowermost position and release it in that position, a set of reciprocating fingers adapted to pass 125 through said slots while grasping a section 130

of cloth during their outstroke and releasing it at the termination of said stroke, means for lifting the table above the level of such fingers and holding it there during 5 the return movement of the fingers, and means for laterally removing said sections from the table while in its raised position.

7. The structure set forth in claim 6, combined with a stop for the sections hinged 10 on a fixed axis above the level of the table and resting on the outer edge thereof in an inclined position whereby on the upward motion of the table the angularity of the stop forces the section backward across the 15 table a slight distance and thereby accurately places it in proper register with the removing means.

8. The combination set forth in claim 6, in which the section removing means comprises 20 a pair of endless sprocket chains supported above the table, extending across it in a direction at right angles to the line of travel of the reciprocating fingers and provided with projecting pins on which the sections 25 may be impaled by the upward movement of the table.

9. In a transfer mechanism for bag machines and the like the combination, with a vertically reciprocating table and means for 30 placing successive bag sections on said table when in its lowermost position, of a horizontally movable fork mounted on a level with the uppermost position of the table, mechanism for moving the bag section on the table 35 toward the fork, and means for lifting said table to a level with the fork when the latter is withdrawn to one side, and subsequently lowering it, and for projecting said fork over the table and under each bag section 40 after the latter has been grasped by the before mentioned moving means, and subsequently withdrawing the fork, whereby each bag section is positively stripped from the table and held in engagement with 45 the moving means.

10. The combination set forth in claim 9, in which the table-moving means has a two-step return movement the first phase of which drops the table a distance equal to 50 the thickness of the fork and maintains it at that level during the movement projecting the fork over the table.

11. In a bag making machine of the type wherein means are employed for printing 55 a repeat design upon a web of cloth and a cutting apparatus adapted to cut said printed web between said designs to produce a series of sections each bearing said printed design, the combination, with said above recited printing means and cutting apparatus, of an intermittently operating mechanism 60 for feeding said printed web to said cutting apparatus so that it may sever the web between said printed designs, said feeding apparatus comprising a manually operating 65

ated device for temporarily slightly accelerating or retarding the surface speed of said web during the continued operation of said feeding mechanism, whereby the registry of said designs with said cutting apparatus 70 may be adjusted from time to time to maintain the accuracy thereof.

12. In a bag making machine the combination of a cloth cutting mechanism, an adjustable feed mechanism for delivering 75 different lengths of cloth to said cutting mechanism, a sewing machine, mechanism adjustable as to width for feeding the cut sections of different dimensions through said sewing machine along a line at right 80 angles to the line of travel of the cloth through the cutting mechanism, and a mechanism for transferring the cut sections from one feeding mechanism to the other.

13. The combination set forth in claim 85 12, in which the transfer mechanism comprises a vertically reciprocating table composed of two sections, one overlapping the other, one fixed and the other movable laterally, and means for adjusting the last named 90 table section correspondingly with the adjustment of width of the sewing machine feeding mechanism.

14. In a bag making machine the combination, with means for folding a web of 95 cloth and cutting it into sections of different dimensions, of a sewing machine mounted on a slide movable in a line parallel to the line of travel of the cloth through the cutting means, a movable stop for the cut sections, a pin sprocket chain mounted on sprocket wheels revoluble in a plane at right angles to the line of travel of the cloth through the cutting means and adapted to feed the cut sections through the sewing 100 machine, means for rotating said sprockets and driving said sewing machine, and mechanism for simultaneously adjusting said sprockets, stop and sewing machine slide to 105 so locate the parts as to handle bag sections of various dimensions delivered from the cutting means.

15. In a bag making machine or the like, the combination of two parallel sets of cloth 110 feeding apparatus, one of which is adjustable laterally of the line of feed, two sewing machines and two sets of driving gearing therefor, the sewing machine and driving gear therefor located adjacent to the adjustable feeding apparatus being mounted 115 on an adjustable base, and means for simultaneously adjusting the position of said base and said adjustable feeding apparatus.

16. In a bag making machine or the like, the combination of a sewing machine, a rotary member for driving the same, a projecting hub permanently geared to the sewing machine, a clutch mechanism connecting the hub and rotating driving member 120 125 130

- and a spring normally holding the clutch in engagement, whereby the operator may grasp the hub when the machine is in operation, disengage the clutch by moving the hub along the line of its axis, and, while the clutch is disengaged, operate the sewing machine slowly by hand independently of the rotary driving member.
17. In a bag making machine the combination, with means for feeding a web of cloth, cutting it into sections, a sewing machine adapted to form said sections into bags, and a thread-cutting apparatus for severing the connecting threads between the bags, of a removable and adjustable base on which the sewing machine, thread-cutting apparatus and driving gearing for said sewing machine and thread-cutting apparatus are mounted; together with a separable coupling, one member of which is carried on the removable base, while the other is mounted on the main frame of the machine and connected to the main driving means thereon, the said parts of said coupling being adapted to be thrown into mesh by the placing of the removable base and mechanism carried thereby in operative position.
18. In a bag making machine or the like, the combination with a table and means for feeding a series of sections of cloth along and beyond the same, of extensions from said table in the line of feed of the sections underlying the edges of the sections fed over the table, endless chains mounted over said extensions and adapted to bear on the edges of the sections resting thereon, and means for forcing each section downward after it has passed beyond the end of the table, thereby freeing it from its frictional engagement with the chains.
19. An apparatus such as set forth in claim 18, in which the removal means comprises, a horizontally projecting member, a horizontally movable carriage on which the said member is pivoted near one end of the member, means for reciprocating said carriage so that the projecting member may extend over the cloth section held by the chains, and mechanism for holding the member up above the level of the cloth section on its forward movement, and for releasing it so that it may fall on each section when it reaches the end of its forward motion.
20. In a bag making machine or the like, the combination with two endless sprocket chains arranged in parallel loops provided with projecting pins for feeding the bags, means for impaling the bag sections on said pins located near one end of the sprocket chain loops, means for rotating the sprockets, a swinging member located near the other end of the chain loops, and mechanism for periodically swinging said member away from the chains to strip the bag sections from the pins.
21. In a bag making machine having a sewing mechanism, and means for feeding a series of bag sections through the sewing mechanism and thereafter severing the connecting threads, the combination with said above recited elements of a delivery belt upon which the separated bags may be deposited of a length several times greater than that of any one of the bags delivered to it and means for intermittently feeding said belt, along the line of the sewing machine feed, at intervals of time sufficient for the accumulation thereon between movements of a predetermined number of bags, whereby a series of piles each containing a predetermined number of bags may be formed on said belt.
22. A combination such as set forth in claim 21, in which the belt feeding mechanism is adjustable both as to extent of the feed motion and as to the frequency of its periods of operation.
23. A combination such as set forth in claim 21 in which the feed movement of said belt is slightly less than the length of the bags delivered to it, whereby the forward edge of the second and each succeeding pile of bags formed thereon rests upon the rear edge of the preceding pile.
